UNITED STATES PATENT OFFICE.

GEORGE LOOP MOORE AND JAMES ROBERT STEELE, OF OWEGO, NEW YORK.

RAIL ANCHOR.

Application filed September 23, 1927. Serial No. 221,479.

Our invention relates to anchoring or anti-creeper devices, and particularly to the anti-creeper devices for railroad rails which extend beneath the rail base, gripping same and so positioned as to coact with a tie of the trackway to check the creeping tendency of the rail.

In our present invention the yoke is preferably a bar of rectangular cross section, shaped by forging or bending. The key member is preferably formed from a rolled channel shaped bar with at least one depending leg extending beneath the transverse under rail portion of the yoke when in operative position.

Our invention has for one of its objects the provision of an improved anti-creeper which is easily applied to the rail base and efficiently grips same to check the creeping tendency of the rail.

A further object of our invention is to provide an improved anti-creeper, the yoke of which is made preferably from a bar of uniform cross section, shaped by forging or bending thus eliminating waste in manufacture.

A further object of our invention is to provide an improved anti-creeper comprising a yoke member and a key member in which the key is formed with a depending leg extending beyond the under rail portion of the yoke whereby the key is brought to bear directly against the side face of the tie when in operative position.

A further object of our improved invention is the provision of a two-piece anchor having a yoke member and a key member which extends downwardly beyond the yoke member whereby the hammering action of the anchor against the ballast of the road bed will be imparted directly to the rail through the key.

The novel features of our invention will be more fully understood from the following description and claims taken with the drawings, in which:

Fig. 1 is a side elevation of our anti-creeper device in position to be applied to the rail base;

Fig. 2 is a side elevation of our anti-creeper device in its loose position on the rail base;

Fig. 3 is a side elevation of our anti-

creeper device in its gripping position after the key member has been driven;

55

Fig. 4 is an end view of the device shown in Fig. 3 with a key having legs of unequal length;

Fig. 5 is a plan view of the key member;

Fig. 6 is a longitudinal cross section of the key member; and,

Fig. 7 is an end view of a modified form of key member with legs of equal length.

Referring to the drawings: 8 indicates a rail and 9 a tie of a railroad trackway. 10 is the yoke member and 11 is the key member of our anti-creeper device. The yoke 10 comprises a transverse under rail portion 12 and inturned hook end portions 13 and 14, respectively. The yoke is preferably formed from a bar of rectangular cross section bar, shaped by forging or bending. The key member 11 is preferably formed from a rolled channel shaped bar which is sheared to length to provide individual keys.

75

The portion 12 of the yoke is spaced sufficiently below the rail base to provide a clearance and room for the reception of the key member 11, and, for further clearance in applying the yoke transversely to the rail base.

To this end, the interior or clearance space is preferably extended outwardly and downwardly below the hook portion 13 as designated by the numeral 15 in Fig. 3, and thus allows this end to engage over the rail base, first by tilting the yoke and then shifting it laterally on to the rail in the manner which will be readily understood from Fig. 1.

The hook end 14 is then raised vertically until the underside of the hook is coplanar with the upper surface of the rail base. The yoke is then moved towards the left into its position, as illustrated in Fig. 2. Beneath the hook end 14 is provided an abutment face 16 to bear solidly against the edge of the rail base and serves to limit the movement of the yoke towards the left, transversely with respect to the rail. In this position of the yoke, the upper edge of the portion 12 is substantially parallel with the bottom of the rail base for the major portion of its length. This upper edge is provided with one or more protuberances or projections 17 for the purpose hereinafter described.

100

The key member 11 comprises a web por-

tion 18 having depending longitudinal leg portions 19 and 19' formed at the marginal edges thereof. The web portion 18 of the key member 11 has formed on its under surface one or more ways 20 which are inclined in its longitudinal direction, the number of such ways depending upon the number of protuberances 17 formed on the yoke with which they are adapted to engage. The inclined ways 20, as shown on the drawings, are formed by deforming the web portion 18 between dies or other suitable means well known to the art of metal working. The leg portions 19 and 19' are shown in Figs. 1 to 6, inclusive, to be of unequal depth; the portion 19 being of sufficient depth to extend below the bottom of the yoke member. Said leg portions are spaced apart a distance slightly greater than the thickness of the yoke member and when the anti-creep device is in operative engagement with the rail base they constitute rigid retaining members which engage the sides of the yoke to prevent lateral relative movement between the latter and the key. The leg portion 19 constitutes a tie abutting member of substantial size. A closed end slot 21 is formed in the web portion 18 of the key member at a point somewhat beyond the transverse center line and extends along the key member but terminates at a point short of the end thereof for the reception of the yoke member 10.

Preparatory to applying our device to the rail base, the key 11 is assembled on the yoke 10 in the position shown in Fig. 1 in the manner set forth in co-pending application for Letters Patent, Serial No. 122,533 filed July 15, 1926. The hook end 14 of the yoke is deformed as at 14', to increase the thickness thereof at that point so as to prevent the removal of the key from the yoke at that end. The yoke is mounted on the rail base in the manner previously described, to its position shown in Fig. 2, and is moved longitudinally of the rail bringing the key into contact with the tie 9, as shown in Fig. 4. In this initial position of the device, it will be seen by referring to Fig. 2 that the protuberances 17 are disposed at the top of the inclined ways 20 and the key is in its lowermost horizontal position with respect to the plane of the bottom of the rail and in this position provides a clearance indicated by the numeral 22, between the latter and the upper surface of the key member. In consequence of such clearance, the device is adaptable to fit rails having different base flange thickness and widths. The extending end of the key is conveniently placed so that it may be struck by a hammer or other implement suitable for the purpose of driving the key transversely of the rail and longitudinally of the yoke.

As the key is driven transversely of the

rail, the abutment face 16 of the yoke bears solidly against the edge of the rail base and prevents the movement of the yoke transversely of the rail. As the key moves longitudinally on the yoke, it is positively guided by the depending leg portions 19 and 19', and the inclined ways 20 engaging the protuberances 17 cause the key to be raised in right lines upwardly so that the upper surface of same is maintained parallel with respect to the bottom surface of the rail base. The key is forced into contact with the latter and causes the device to firmly grip the rail. It will be seen that the key member is of considerable length, compared with the length of the under rail portion 12, and when our device effectively engages the rail, the key extends almost entirely across the bottom of the rail and imparts thereto an upward bearing pressure which is uniformly distributed and secures a strong gripping action on the rail and allows the full length of the key to bear against the tie and provides a substantial bearing surface to coact with the tie to effectively check any further creeping tendency of the rail.

By referring to Fig. 5 it will be noted that the legs 19 and 19' extend beyond the end of the web portion 18. This extension is sufficient so that when the anchor is in its effective position, as shown in Fig. 3, the ends of the legs are preferably flush or extend beyond the contiguous edge of the rail flange. This extension serves the purpose of a gage and indicates to the trackman that the key member 11 has been driven to its effective position with respect to the yoke and the rail.

Referring to Fig. 7 we show a key member having the depending legs 19 and 19' of equal length. With a key of this type, either of the legs constitutes a tie abutting member. Thus our device may be effectively applied to the rail at either side thereof and at either side of the tie.

From the foregoing description it will be seen that we have devised an improved anti-creep, which is rigid in construction, is easily applied to the rail base and efficiently grips same to check the creeping tendency of the rail. The yoke member formed of a continuous bar and bent or forged to shape provides greater bearing surface in contact with the top of the rail base, and eliminates waste in manufacture. The key member, by the increased depth of a depending leg affords greater bearing surface in contact with the side face of a tie in directions both longitudinally and vertically of the same, whereby the yoke is relieved of contact with the tie, and at the same time the possible effect of the device hammering on frozen ballast is transmitted directly to the base of the rail through the key and reduces to a minimum the loosening tendency between the key and the rail.

and yoke. Furthermore, the key member is extended beyond the rail base and is accessible to the track operator so that it is conveniently driven without the use of special 5 tools.

A device constructed in accordance with our invention has many advantages over the so-called one-piece anti-creeper, for instance, a single piece device becomes ineffective 10 when the rail to which it is applied becomes worn or corroded and must be replaced, whereas, a device employing our invention may be rendered just as effective as when originally applied to the rail by merely 15 driving the key member with any suitable implement which may be at hand. Thus a track walker observing a loose anti-creeper embodying our invention may easily place it in an effective condition without replacements or the use of special driving tools.

While we have shown our invention in but two forms it will be obvious to those skilled in the art that it is not so limited, but is susceptible of various other changes and modifications without departing from the spirit thereof, and we desire, therefore, that only such limitations shall be placed thereupon as are imposed by the prior art or as are specifically set forth in the appended 10 claims.

Having thus described our invention what we claim as new and desire to secure by Letters Patent is:

1. An anti-creeper comprising a yoke having hooked ends to engage the upper surface of the base flange of a rail; and an under rail portion in spaced relation with respect to the bottom of the rail, one or more protuberances projecting upwardly from 35 said portion, a key having a relatively large bearing surface for engaging the under surface of the rail base, and one or more inclined ways formed on said key adapted to engage said protuberances, said key having 40 one or more depending members extending below said yoke when the anti-creeper is mounted in its operative position on the rail.

2. An anti-creeper for rails comprising a yoke, a key extending longitudinally of said yoke and having a closed end slot to receive the yoke, and members depending from said key for engaging the sides of said yoke, one of said depending members extending below 55 said yoke when in operative position on the rail.

3. An anti-creeper device comprising a yoke having an under rail portion and hooked ends thereof to be adapted to engage the base of a rail, and a key adapted to rest 60 on said portion and project below the underside of said yoke.

4. An anti-creeper for rails comprising a yoke having an under rail portion, and a key member having a closed slot formed 65 therein receptive of said yoke, said key be-

ing of such a length that it extends beyond the edge of the rail base and of a depth at least equal to the under rail portion of said yoke.

5. An anti-creeper for rails comprising a 70 yoke with hooked ends, and a key, said key having an opening formed therein receptive of one of said hooked ends, one of said hooked ends being deformed to prevent the removal of the key from the yoke at the last 75 mentioned hooked end.

6. An anti-creeper for rails, a yoke having hooked ends and an under rail portion, a projection extending from said under rail portion, a key member adapted to rest on 80 said projection and having an inclined way adapted to coact with said projection to raise said key when the latter is moved longitudinally, said key having depending side legs one longer than the other, said long leg 85 forming a tie abutting member.

7. In an anti-creeper for rails, a key comprising a web portion having a protuberance constituting an inclined way and having a certain portion of its length removed to 90 constitute an elongated slot, and leg portions extending downwardly from said web portion, one of said legs being longer than the other.

8. An anti-creeper for rails, comprising a 95 yoke adapted to extend beneath the rail and having hooked ends thereof extending inwardly over the base of the rail, and a key member adapted to be driven between said yoke and the bottom of the rail, said key 100 member being of such a length that upward bearing pressure is applied to the bottom of the rail across substantially the entire width of its base flange when in its operative position, said key having depending leg portions 105 extending substantially the full length of the key and at least one leg adapted to abut a tie and to project below said yoke when in operative position on the rail.

9. An anti-creeper for rails comprising 110 a yoke having hooked ends and an under rail portion, one or more protuberances formed on said portion, a key member having a closed slot receptive of one of the hooked ends aforesaid, the latter end being 115 deformed to prevent the removal of the key member therefrom, one or more inclined ways formed on said key for engaging said protuberances, and one or more tie abutting members, said abutting member extending 120 below said under rail portion, said yoke being free of tie engagement when in operative position on the rail.

10. In a railway track structure the combination of a foundation, a tie resting on said 125 foundation, a rail supported on said tie, an anchoring device comprising a member engaging said rail, but disposed in spaced relation with respect to the underside of the rail base and a key interposed between said 130

member and the underside of the rail base having a portion thereof extending below said member whereby the forces imposed on said device by its pounding on said foundation will be transmitted through the key directly to the rail.

11. An anchoring device comprising a member, and a key member adapted to

straddle and to be moved longitudinally of said member and having a portion thereof extending downwardly beyond the underside of said member.

In testimony whereof we hereunto affix our signatures.

GEORGE LOOP MOORE.
JAMES ROBERT STEELE.
